UNITED STATES PATENT OFFICE.

PHILLIP GOEHRING, OF SEATTLE, WASHINGTON.

DESIGN FOR A TOY.

58,142.

Specification for Design.

Patented June 14, 1921.

Application filed April 4, 1921. Serial No. 458,538. Term of patent 7 years.

To all whom it may concern:

Be it known that I, PHILLIP GOEHRING, a citizen of the United States, residing in the city of Seattle, in the county of King and State of Washington, have invented a new, original, and ornamental Design for a Toy, of which the following is a specification, reference being had to the accompanying drawings, forming a part thereof.

Figure 1 is a top plan view of a toy showing my new design; and

Fig. 2 is a view in medially vertical transverse section of the same, with the spherical element shown in one of the concavities of the toy.

I claim:

The ornamental design for a toy as shown.
PHILLIP GOEHRING.
